UNITED STATES PATENT OFFICE.

FRANK ROBERSON DEXTER, OF DAYTON, OHIO.

AUTOMATIC BLOW-OFF DEVICE.

1,294,061.

Specification of Letters Patent.

Patented Feb. 11, 1919.

Application filed January 30, 1918. Serial No. 214,470.

To all whom it may concern:

Be it known that I, FRANK ROBERSON DEXTER, a citizen of the United States, and a resident of Dayton, in the county of 5 Montgomery and State of Ohio, have invented a new and Improved Automatic Blow-Off Device, of which the following is a full, clear, and exact description.

This invention relates to steam boilers or other analogous appliances and has particular reference to attachments for such appliances whereby predetermined or regulated quantities of the contents thereof are adapted to be delivered therefrom.

10 More definitely stated among the objects of this invention is to provide an attachment for a steam boiler whereby any deposits of sediment, scale, sand, grit, or other solid particles may be discharged 15 from within the boiler by means operated automatically at any desired rate of speed by reason of the internal pressure.

A further object of the invention is to provide an attachment of the general character above indicated for connection to or use in conjunction with the blow-off pipe of a steam boiler whereby, as a result of certain adjustments to be described fully below, either the whole of the contents of 20 the boiler may be discharged directly into the sewer or other place of delivery, or else regulatable quantities less than all of the contents may be discharged. By the use of the term "steam boiler" herein I desire it 25 to be distinctly understood that I mean to cover not only steam boilers proper but feed water heaters or other containers having relatively high internal pressure.

With the foregoing and other objects in 30 view the invention consists in the arrangement and combination of parts hereinafter described and claimed, and while the invention is not restricted to the exact details of construction disclosed or suggested here- 35 in still for the purpose of illustrating a practical embodiment thereof reference is had to the accompanying drawings, in which like reference characters designate the same parts in the several views, and in 40 which

Figure 1 is a vertical longitudinal section of my improvement.

Fig. 2 is a similar view, but with the reciprocating piston in the position in which 45 it is presumed to be moving toward the right; and

Fig. 3 is an enlarged detail view of the pilot valve in open position.

Referring now more particularly to the drawings I show a device comprising a 50 main casing or body 10 comprising two main chambers 11 and 12 in the nature of coaxial cylinders, the former being smaller in cross section than the latter.

13 indicates a blow-off pipe leading from 55 the boiler or a connection with the blow-off pipe. This member which will be referred to herein as the blow-off pipe is tapped into or otherwise secured to the nipple portion 14 of the body from which 60 a passageway 15 leads into the smaller cylinder or chamber 11. In line, however, with the blow-off pipe I provide a by-pass 16 leading directly to the delivery pipe 17 connected with the discharge nipple 18 at 65 the lower portion of the body, this nipple being in communication with the larger cylinder 12 beyond the end of the cylinder 11.

At one side of the cylinder 11, preferably 70 the upper side, is connected through a neck 19 a closed chamber 20 or dome of any desired capacity.

A slide valve 21 having a threaded shank 22 is fitted in the body so as to control the 75 delivery of the materials through the by-pass 16. When the valve 21 is in the position indicated communication is cut off through the by-pass, but the shank 22 being extended up through the top wall of the 80 body and provided with a nut 23 may be adjusted upward so as to open a direct communication from the blow-off pipe through the by-pass when it is desired to empty the boiler. Ordinarily, however, or 85 especially in connection with the automatic means referred to below the valve 21 is retained in its closed position indicated.

24 and 25 are two pistons secured for simultaneous reciprocation and in spaced 90 relation to each other by means of a rigid connector 26, said pistons being fitted for reciprocation in the respective cylinders 11 and 12. The piston 24 in the position of Fig. 1 lies at one side of the neck 19, remote 95 from the admission end of the body, so that any material or contents of the boiler may be delivered into the dome 20 until said dome is filled. After the piston 24 reciprocates, however, to its opposite position to 100 which it is approaching, as shown in Fig. 2, communication between the passageway 15

and the dome is cut off and the delivery from the dome through the neck 19 is opened at the left of the piston 24 through the inner end of the cylinder 12 to the delivery pipe 17. This action or position of the piston 24, opening the dome to communication with the delivery pipe, serves to bring the interior of the dome ordinarily to atmospheric pressure. When I referred just above to the filling of the dome, as in Fig. 1, I, of course, contemplate that any air that may be trapped in the dome will simply be subjected to the boiler pressure during the filling action so that when the piston 24 is in its cut off position as in Fig. 2 the pressure of such trapped air, remaining practically equivalent to the boiler pressure, will act to forcibly eject the contents of the dome into the sewer.

Any suitable means may be provided to reciprocate the piston 24 for the purpose of alternately opening communication to and providing for delivery from the dome 20. To this end I employ the piston 25, which being fitted in the larger cylinder has the larger cross sectional area. At any convenient place as at the cap 27, I provide a live steam inlet for the cylinder 12. This inlet is indicated at 28 and is provided with a manually controlled valve 29 through which the live steam or analogous high pressure fluid may be delivered into the outer end of the cylinder 12 to act against the outer face of the piston 25 at any desired speed preferably relatively low speed. Since the area of the piston 25 is superior to that of the other piston, the pressure fluid acting inward against the piston 25 from the position of Fig. 1 will move the double piston structure toward the right, and as soon as the piston 24 passes beyond the neck 19 the contents of the dome being under high pressure will be discharged through the delivery pipe 17 as shown by the arrows on Fig. 2, and the pistons will continue moving in the same direction until the piston 25 abuts against the annular shoulder 30 constituting the inner end of the wall of the cylinder 11.

31 indicates a pilot valve projecting through a hole 32 in the piston 25 adjacent to one side of the piston and parallel to its axis. This pilot valve is slightly longer than the length of the piston and has on its outer end a head 33. The inner end of the pilot valve while the piston is moving toward the right impinges against the shoulder 30 while the piston is approaching the end of the stroke, and so the pilot valve is moved relatively toward the left bringing the channel 31' thereof into action to establish communication directly from the cylinder 12 to the delivery pipe. The capacity of the port 31' is ordinarily greater than that of the inlet controlled by the valve 29 and hence the power fluid admitted into the

cylinder 12 while the pilot valve is open flows directly through the pilot valve and hence has no tendency or power to resist the return movement of the piston toward the left under the force of the constant pressure of the boiler acting against the outer or right hand end of the piston 24 so the pistons are returned to the positions of Fig. 1, the pilot valve remaining open until its head strikes against the cap 27 at the end of the cylinder 12. Therefore, as soon as the pilot valve is thus closed the power pressure admitted against the outer end of the piston 25 will again drive the piston toward the right with a repetition of the action already described, thus the valve 24 will be reciprocated to and fro continually by virtue of the steam pressure applied to the piston 25, the rapidity of such reciprocation being determined by the design of the device and relative areas of the inlet and pilot ports.

The device is of a simple construction and is safe and reliable in operation requiring but a slight degree of expense for installation and in no manner interferes with the ordinary operation of the blow-off pipe. If a complete blow-off is desired the valve 21 will be opened as already stated.

I claim:

1. In a blow-off valve, the combination of a body having a cylindrical chamber and having a passageway at one end leading from the attached pipe, a closed receptacle communicating with one side of the cylinder, a piston slidably fitted in the cylinder and movable to and fro across the neck leading to the receptacle, and means actuated automatically from the power fluid to which the device is connected for reciprocating said piston.

2. In a device of the character set forth, the combination of a body, a pipe connecting the body to a boiler, said body including a cylinder, a closed receptacle having an open passageway leading from one side of the cylinder, a piston movable to and fro in the cylinder across the passageway, the other end of the cylinder being open for free discharge of material from the receptacle when the piston is at the remote side of the passageway from the outlet, and automatic means acting upon the piston to cause it to reciprocate into a position to allow the contents of the receptacle to discharge freely through the outlet.

3. In an automatic valve, a hollow body including two cylinders one larger than the other in cross section, inlet means at the opposite ends of the body whereby a power fluid from the same source may be admitted into both cylinders, a pair of rigidly connected pistons fitted in the respective cylinders, means to control the inflow of power fluid, the larger piston serving to overbalance and drive the smaller piston to the op-

posite end of the body, and means to automatically reduce the excessive pressure against the larger piston and so permit the constant pressure against the smaller piston 5 to reciprocate the pistons in the opposite direction.

4. In an automatic valve, the combination of a body having two co-axial cylinders one larger than the other, a pair of pistons fitted 10 in said cylinders, means rigidly connecting the pistons in spaced relation to each other,

means to admit power fluid into the opposite ends of both cylinders to act against the outer ends of the pistons respectively, a discharge pipe from one side of the body adjacent to the inner meeting ends of the cylinders, and a pilot valve extending through the larger piston acting to open and close communication through said piston automatically at the respective ends of the reciprocations of the piston. 15 20

FRANK ROBERSON DEXTER.
